UNITED STATES PATENT OFFICE.

HIRAM E. BALDWIN, OF CLEVELAND, OHIO, ASSIGNOR TO THE BROWN HOISTING MACHINERY COMPANY, OF CLEVELAND, OHIO, A CORPORATION.

MEANS FOR OPERATING RAIL CLAMPS.

Application filed September 22, 1924, Serial No. 739,218.

To all whom it may concern:

Be it known that I, HIRAM E. BALDWIN, a citizen of the United States, residing in the city of Cleveland, county of Cuyahoga, 5 and State of Ohio, have invented a new and useful Improvement in Means for Operating Rail Clamps, of which the following is a clear and exact description, reference being made to the accompanying drawing, 10 which forms part of the specification, and wherein the same parts are designated by the same characters in each case.

My invention relates to clamping devices of the kind that are employed on large 15 traveling bridge-cranes, such as are used in the ore and coal handling trades, to hold the bridges securely, when at a state of rest, to the rails upon which they travel. Broadly considered, the invention is appli- 20 cable to any structure that is mounted on wheels and movable on rails.

The principal object of my invention is to provide a simple, sure and efficient means 25 for releasing clamping devices of the kind in question, when it is desired to move the bridge-structure from place to place along the supporting rails.

Another object is to provide means to 30 control the clamp setting-mechanism to prevent a sudden or abrupt application of the clamping-members to the heads of the track- rails.

Furthermore, to furnish a device that is 35 so calculated that the electric system for its operation may be coordinated in such manner with the system for traveling the bridge-structure, that it will be impossible for the device to function prematurely, but only when the bridge-structure itself is at 40 rest, and as a preliminary to its movement along the rails.

The character of the invention will be 45 readily understood upon reference to the drawing, and, when considered in conjunction with the specifications.

In the said drawing Figure I, is a fragmentary side view of a traveling bridge-crane sill upon which is mounted a pair of rail clamping members and the necessary 50 parts and mechanism for actuating the said clamping-members; Figure II is a plan view of the constituent parts shown in Figure I, together with the electrical elements, shown graphically, required to operate the 55 clamp controlling means in coordination

with similar elements for traveling the crane, and Figure III is a sectional view taken in the line ABC of Figure I.

Referring to the drawing S is a bridge-crane sill, whose supporting wheels W, W 60 are adapted to travel on a track rail T. Depending from the sides of the sill S and intermediate of its supporting wheels are two pairs of guide or chock-plates P, P¹ and P², P³. 65

A trolley t, mounted on rollers r, r that rest on the track-rail T, is located under the sill S between the pairs of plates P, P¹ and P², P³, respectively. It is provided at its ends with upwardly projecting pieces 70 p, p, p, p that engage the sides of the sills to prevent any transverse displacement of the same. The trolley is propelled along the rail T by means of the pairs of plates P¹, P², and P³, respectively, according 75 to the direction of travel, when the bridge-crane is moved from place to place along its track. Midway of the trolley t and spaced apart are pairs of transversely extending ears, e, e and e¹, e¹ provided with 80 pin-holes to receive clamp carrying pins E, E¹.

Right and left rail clamping-members R and L are placed on the pins E, E¹ between the pairs of ears e¹, e¹ and e, e respectively. The lower ends of the clamping-members extend downwardly and inwardly to points near the sides of the head of the rail T and the upper ends extend upwardly and terminate at points immediately above 90 the sill S. The upper ends are bifurcated to receive toggle-links l, l. Pins k, k, connect the links l, l to the clamping-members R and L respectively. 85

The toggle-links l, l are of such length, 95 center to center of pin-holes, that when they are connected to the clamping-members R and L by the pins k, k, with said clamping-members in contact with the sides of the head of the rail T, the inner ends, when 100 joined together by the pin K¹, will be above the horizontal plane passing through the outer pin-holes and the pins k.

Mounted on the sill S to the right and left of the clamping-members R and L 105 (see Fig. I) at points that are equidistant therefrom are cylinder supporting-brackets b, b. Above the links l, l, between the brackets b, b and fastened to the latter is a cylinder M whose piston D through its con- 110

necting-rod G is adapted to actuate the toggle-links, l, l and thereby the clamping members R and L.

Normally the piston D is near the lower 5 end of the cylinder M; the connecting-rod G which is fastened to it extends downwardly through the lower cylinder-head, and terminates in a bifurcated or forked end which embraces the inner ends of the 10 toggle-links l, l and to which inner ends it is connected by the pin K¹. Inserted in the cylinder M, between the piston D and the upper cylinder-head, is a resilient member, preferably as shown, a clamp-setting spring 15 O, whose function is to keep the piston D at its normal position and in consequence, the clamping-members, R and L firmly set against the sides of the head of the rail T.

Clamp releasing mechanism comprising a 20 motor N, a fluid pump F, a fluid supply-tank or reservoir f, a valve V (held normally open with a spring and closed, electrically, by a solenoid), a fluid regulating valve RV and the necessary piping are located on the 25 top of the sill S adjacent to the cylinder M. A pipe 20 leads from the supply tank f to the intake of the fluid pump F; a pipe 21 leads from the discharge side of the pump F to the intake of the cylinder M which is 30 located below the piston D when the latter is in its normal position; a pipe 22 leads from an overflow outlet x in the cylinder M to the supply tank f; a pipe 23, which has the solenoid valve V and the regulating 35 valve RV in its line, leads from the pipe 21 to the supply tank f. The motor N is adapted to drive the fluid pump spur-pinion sp on the motor shaft and the spur-gear sg on the pump shaft ps. An interlock, or plunger-switch, 24 is located above the cylinder 40 M; its operating rod or stem 24^a extends downwardly through the upper cylinder head into the cylinder M to a distance that will insure an upward movement of the same 45 during the release stroke of the piston after the clamp-members have become disengaged from the rail head.

The details of a preferential electrical 50 system comprising in their proper sequence and location, the wiring, resistances, solenoids, terminals, contactors, interlocks, switches, and other contributing elements, for the functioning of an overhead crane in its movements along a track, and also the 55 designed workings of the device under such conditions are indicated diagrammatically in Fig. II and with sufficient definiteness it is thought, for the full understanding of the same by those versed in the art.

60 A master-switch MS, through the several contactors and interlocks, controls the circuits to the pump-motor N, the solenoid valve V and the bridge travel-motor.

65 On referring to the wiring diagram in Figure II, it will be apparent, that when the

master-switch MS is advanced (either forward or reverse) the electric current will immediately flow to the pump-motor N and to the normally open solenoid-valve V; in consequence of which the motor will start 70 and the valve V will close. The pump is now functioning under the influence of the motor and the fluid is introduced into the cylinder M through the pipe 21 below the piston D. When the pressure of the fluid against the underside of the piston is sufficient to overcome the pressure of the spring O, the piston will rise until its lower surface is above the opening x in the cylinder. The upward travel of the piston will 75 raise the toggle-links l, l, and thereby draw the upper ends of the clamp-members L and R together and separate their lower or gripping ends from the rail head. As soon as the clamp-members are thus fully released 80 from the rail, the piston D encounters the stem 24^a of the interlock 24 and carries the same with it until it reaches the end of its upward travel. In this manner as soon as the piston D is at its upper travel limit the interlock 24 is closed, and then, and not before, will current flow to the bridge travel-motor, (not shown), and the bridge structure, 85 of which only the sill S is shown, will start to travel along the rail T. It is evident from the foregoing description that the pump motor will function continuously while the bridge motor is traveling the bridge structure; to prevent any undue 90 strains and pressures on the pump and the cylinder while the bridge is traveling any excess pressure in the cylinder is relieved by the escapement of the fluid through the opening x into the pipe line 22, which conducts 95 the fluid back to the supply tank f.

When the bridge has traveled to the location desired the master-switch or controller is turned to the neutral or "off" position. With the controller in this position all current is shut off from the several electrical 100 units (the bridge travel-motor, the solenoid valve V and the pump-motor N), and the same cease to function.

As will be evident, by the time the bridge-structure has been brought to rest by the action of the bridge travel-motor's brake, the piston, having been relieved of the fluid pressure beneath, will no longer resist the expansive force of the spring O, and, in consequence, under the influence of that force, 105 will have descended to its normal position and the clamping-arms R and L, have re-engaged the rail as designed.

It is obvious that, during its descent to its 110 normal position, the piston will force the fluid that was under pressure during the traveling of the bridge-structure, back to the supply tank through the pipes 22 and 23, the normally-open solenoid valve V, and the 115 regulating valve RV. The purpose of the 120

valve RV, in the pipe line 23, is to regulate the speed at which the fluid is returned to the tank and thereby provide against a sudden or too abrupt application of the clamp-
5 members against the rail head T. It follows, of course, that, when the piston breaks contact with the stem 24^a, the interlock switch 24 will open and the travel-motor cease to function.

10 Having described my said invention, and shown a concrete application of the same, what I wish to secure by Letters Patent is:

1. A clamping device for securing overhead cranes and similar structures to their supporting rails, comprising the combination of oppositely disposed clamping arms pivotally connected to and beneath the structure, jaws at the lower ends of the arms, links jointedly fastened to the upper ends of
15 said arms and projecting equidistantly therefrom towards each other, a fluid-cylinder supported on said structure, at a predetermined point above said links, a piston within the cylinder normally located
20 near the lower end thereof, a connecting-rod depending from said piston and extending downwardly through an aperture in the lower head of the cylinder, for the purpose, to and into operative engagement with the
25 inner ends of said links, a resilient piston-resisting member between said piston and the upper head of said cylinder, an intake-orifice in the cylinder below said normal location of said piston, a plunger contactor-
30 switch above said cylinder with its stem extending downwardly through the upper head of the cylinder to a predetermined point in the upward part of said cylinder, clamp-releasing mechanism, supported on
35 said structure, comprising a fluid reservoir, a fluid-pump, a motor for operating said pump, a pipe between the reservoir and the pump, a pipe between the discharge side of the pump and said intake-orifice, a pipe, having
40 a normally open solenoid-valve in the same, between the pipe last above named and said reservoir, all substantially as shown and described.

2. A clamping device for securing overhead cranes and similar structures to their supporting rails, comprising the combination of oppositely disposed clamping arms pivotally connected to and beneath the structure, jaws at the lower ends of the arms, links jointedly fastened to their upper ends and projecting equidistantly therefrom towards each other, a fluid-cylinder supported on said structure at a predetermined point above said links, a piston within the cylinder normally located near the lower end thereof, a connecting-rod depending from said piston and extending from said piston downwardly through an aperture in the lower head of the cylinder, for the purpose, to and into operative engagement with the
55 lower head of the cylinder, for the purpose,
60 to and into operative engagement with the
65

inner ends of said links, a resilient piston-resisting member between said piston and the upper head of said cylinder, an intake orifice in the cylinder below said normal location of the piston, an outlet orifice in the cylinder below the upward limit of travel of the piston, a plunger contactor-switch above the cylinder with its stem extending downwardly to a predetermined point in the upward path of said travel, clamp-releasing mechanism, supported on said structure, comprising a fluid reservoir, a fluid-pump, a motor for operating said pump, a pipe between the reservoir and the pump, a pipe between the discharge side of the pump and said intake orifice, a pipe between said reservoir and said outlet orifice, a pipe having a normally open solenoid-valve in the same, between said pipe leading to said intake orifice and said reservoir, substantially as shown and described.

3. A clamping device for securing overhead cranes and similar structures to their supporting rails, comprising the combination of oppositely disposed clamping-arms pivotally connected to and beneath the structure, jaws at the lower ends of the arms, links jointedly fastened to the upper ends of said arms and projecting equidistantly therefrom towards each other, a fluid-cylinder supported on said structure at a predetermined point above said links, a piston within the cylinder normally located near the lower end thereof, a connecting-rod depending from said piston and extending downwardly through an aperture in the lower head of the cylinder, for the purpose, to and into operative engagement with the inner ends of said links, a resilient piston-resisting member between said piston and the upper head of the cylinder, an intake-orifice in the cylinder below said normal location of said piston, a plunger contactor-switch above said cylinder with its stem extending downwardly through the upper head of the cylinder to a predetermined point in the upward path of said piston, clamp-releasing mechanism, supported in said structure, comprising a fluid reservoir, a fluid-pump, a motor for operating said pump, a pipe between the reservoir and the pump, a pipe between the discharge side of the pump and said intake-orifice, a pipe, having a normally open solenoid-valve in the same, between the pipe last above named and said reservoir, together with a system of electric circuits that includes said plunger-switch, for energizing said pump-motor, said solenoid-valve, and the motor for traveling the bridge-crane, substantially as shown and described.
